Harold A. Owen, Dover, Del., assignor to International Latex Corporation, Dover, Del., a corporation of Delaware

Application January 15, 1953, Serial No. 23,154

Term of patent 14 years

(Cl. D3—26)

To all whom it may concern:

Be it known that I, Harold A. Owen, a citizen of the United States and a resident of Dover, in the county of Kent and State of Delaware, have invented a new, original, and ornamental Design for a Bib, of which the following is a specification, reference being had to the accompanying drawing, forming part thereof, wherein:

Fig. 1 is a front view of a bib embodying my new design;

Fig. 2 is a back view of the bib shown in Fig. 1;

Fig. 3 is a top view of the bib shown in Figs. 1 and 2;

Fig. 4 is a side view of the bib shown in Figs. 1, 2 and 3.

I claim:

The ornamental design for a bib, as shown.

HAROLD A. OWEN.
